[57] CLAIM

The ornamental design for a bowling shoe sole guard, as shown and described.

DESCRIPTION

FIG. 1 is a bottom plan view of a bowling shoe sole guard showing my new design;

FIG. 2 is a left front perspective view of the bowling shoe guard showing my new design.

The broken lines of a shoe in FIG. 2 are for illustrative purposes only and form no part of the claimed design. The right side of the guard is a mirror image of the left side.

The left side is a mirror image of the right and the double rows of stitching are continuous around the entire periphery.
